(57) **CLAIM**

I claim the novel ornamental design for an LED lamp, as shown.

DESCRIPTION

FIG. 1 is a front, left, top perspective view of an LED lamp showing a first embodiment of my new design;

FIG. 2 is a front elevation view of the LED lamp of FIG. 1;
FIG. 3 is a rear elevation view of the LED lamp of FIG. 1;
FIG. 4 is a left side elevation view of the LED lamp of FIG. 1;

FIG. 5 is a right side elevation view of the LED lamp of FIG. 1;

FIG. 6 is a top plan view of the LED lamp of FIG. 1;
FIG. 7 is a bottom plan view of the LED lamp of FIG. 1; and

FIG. 8 is a front, left, top perspective view of an LED lamp of showing a second embodiment of my new design;
FIG. 9 is a front elevation view of the LED lamp of FIG. 8;
FIG. 10 is a rear elevation view of the LED lamp of FIG. 8;
FIG. 11 is a left side elevation view of the LED lamp of FIG. 8;

FIG. 12 is a right side elevation view of the LED lamp of FIG. 8;

FIG. 13 is a top plan view of the LED lamp of FIG. 8; and,
FIG. 14 is a bottom plan view of the LED lamp of FIG. 8.
